Specification for Design.

Patented Dec. 10, 1912.

Application filed September 30, 1912. Serial No. 723,263. Term of patent 14 years.

To all whom it may concern:

Be it known that I, FURMAN D. SPEAR, a citizen of the United States, residing at New York, in the county of New York and State of New York, have invented a new, original, and ornamental Design for Signal-Lamps, of which the following is a specification.

The accompanying drawing represents an elevation of a signal lamp showing this design.

The essential features of this design comprise a lamp body A which is spheroidal or

approximately globular in form, and flat upright bars or ribs B of crescent shape arranged edgewise on the outer side of the body and following in their outline or configuration the curvature of the body.

I claim:

The ornamental design for a signal lamp, as shown and described.
